UNITED STATES PATENT OFFICE.

RAY H. SWERDFEGER, OF LOS ANGELES, CALIFORNIA.

RECEPTACLE.

1,305,630.

Specification of Letters Patent. Patented June 3, 1919.

Application filed November 28, 1917. Serial No. 204,410.

To all whom it may concern:

Be it known that I, RAY H. SWERDFEGER, a citizen of the United States, residing at Los Angeles, in the county of Los Angeles and State of California, have invented a new and useful Receptacle, of which the following is a specification.

The present invention relates to receptacles, particularly of the type adapted to contain tobacco, snuff, spices, and other commodities usually packed in containers constructed of tin.

An object of the present invention is to provide a container of this character of a construction which admits of the forming of the container of fibrous material, such as paper; to impregnate the fibrous material with wax oil, paraffin, or a like substance to render the receptacle moisture proof and thus obviate the necessity of using the usual moisture proof lining; and to provide a receptacle or container which is strong and durable, and which may be economically produced.

The above, and various other objects and advantages of this invention will in part be described, and in part be understood, from the following detailed description of the present preferred embodiment, the same being illustrated in the accompanying drawing, wherein:

Figure 1 is a perspective view of a receptacle constructed according to the present invention.

Fig. 2 is a longitudinal section taken through the same.

Fig. 3 is a transverse section taken through the receptacle on the plane indicated by the line 3—3 of Fig. 2.

Fig. 4 is a transverse section through the upper end of the receptacle taken on the plane indicated by the line 4—4 of Fig. 2, showing the hinge joint between the body and the cover of the receptacle.

Fig. 5 is a fragmentary sectional view through one of the upper corners of the receptacle, showing the cover closed.

Fig. 6 is a fragmentary sectional view through the upper end of the receptacle, showing the front wall and the cover overlapping and interlocking therewith.

Fig. 7 is a similar view of one of the lower corners of the receptacle.

Fig. 8 is a view similar to Fig. 3, showing a slightly modified form of reinforcement for the body of the receptacle.

Referring to this drawing 10 designates the body part of the receptacle which may be made of any suitable fibrous material, such as paper pulp suitably compressed and molded to the desired form, or which may be otherwise suitably constructed. This body part 10 is preferably impregnated with a water proofing composition of any desired ingredients dependent upon the material to be packed in the receptacle.

A bottom plate 11 conforming in contour to the cross sectional shape of the body 10, and preferably constructed from the same material as that of the body is fitted in the lower end thereof and may be of slightly greater dimensions than that of the receptacle, as shown in Fig. 2, and about the marginal edge of which is overturned a flange 12 comprising the lower edge portion of the body. The flange 12 is rolled over against the under side of the bottom plate 11 to retain it in place.

The body 10 is reinforced by the provision of a plurality of longitudinally extending strands of wire or the like as indicated at 13, the strands 13 being embedded in the material of the body 10 as shown in Figs. 1 to 7, and which may lie against the inner wall of the body as shown at 14 in Fig. 8. As shown in detail in Fig. 7, the wire strands 13 extend into the lower edge portion or flange 12 of the body. The strands 13 are bent over with the flange and serve to reinforce it and retain the flange in position against the under side of the bottom plate 11.

The upper edge portion of the body 10 is reinforced by an annular strand 15 embedded or otherwise suitably located in the body 10, and to which the upper ends of the longitudinal strands 13 are secured. The upper ends of the strands 13 are rolled over to form eyes 16 which encircle the annular strand 15 to form therewith a reinforcing frame for strengthening the same.

The rear wall of the container 10 is provided with spaced apart recesses opening through the upper edge of the body and extending to a point slightly below the annular strand 15 and within which are adapted to fit tongues 17 depending from the rear edge portion of a cap or closure 18. The tongues 17 engage in said recesses and are rolled over or are enlarged and longitudinally apertured to form eyes receiving the portions of the strand 15 which ex-

tends through the recesses, and the intermediate portion of the body 10 located between the recesses is similarly enlarged and receives the strand 15 there through to form 5 a reinforcing tongue 19 for supporting the closure 18. The tongues 17 turn upon the strand 15 and serve as a hinged connection for the closure. The cap 18 is formed of material the same as that of the body 10 and the bottom plate 11, and has a depending 10 annular flange 20 adapted to engage about the upper edge of the body 10 when the cap is closed.

If desired any suitable friction locking 15 means may be employed for holding the cap 18 closed. In the present instance the front wall of the body 10 and the forward portion of the flange 20 are crimped or pressed inwardly to form a recess 21 in the 20 front wall and a dent 22 in the flange of the cap adapted to drop into the depression 21 and to frictionally hold the cap closed.

The material to be packed may be placed 25 directly within the body of the container and no lining or intermediate packing is required as the substance with which the body is impregnated excludes air and moisture, and the cap 18, which is also treated 30 with the moisture and air proof substance, is adapted to fit tight upon the body.

It is of course understood that various changes and modifications may be made in the above specifically described embodiment

of this invention without departing from 35 the spirit thereof the changes being restricted only by the scope of the following claims.

What is claimed is:

1. A container comprising a fibrous body, 40 longitudinal strands arranged within the body for strengthening the same, and an annular strand arranged within the body, the ends of said longitudinal strands being coiled about said annular strand. 45

2. A container comprising a body portion of fibrous material, an annular reinforcing ring embedded in the body portion near its upper end, said body portion having recesses in its upper end extending below 50 said ring, and a cap fitting on the upper end of the body portion and having depending tongues pivotally engaging the ring in said recesses to connect the cap to the body portion. 55

3. A container comprising a fibrous body, an annular reinforcing ring embedded in the body, a short distance below its upper end, a plurality of longitudinal reinforcing strands in said body and having their upper ends rolled about said ring, said body having recesses in its upper end extending below said annular ring, a cap fitting on the upper end of the body, depending tongues formed upon the cap and engaging 60 said ring in said recesses to connect the cap to the body. 65

RAY H. SWERDFEGER.
